UNITED STATES PATENT OFFICE.

CHARLES D. P. WATTERS, OF NEW YORK, N. Y.

DESIGN FOR A FIREMAN'S HAT.

Specification forming part of Design No. 5,560, dated February 27, 1872.

To all whom it may concern:

Be it known that I, CHARLES D. P. WATTERS, of the city, county, and State of New York, have invented a new and original Design for a Fireman's Hat, the nature of my design being fully represented in the accompanying photographic illustration, to which reference is made.

In the photographic illustration I have shown two views, one of a fireman's hat made after the design I claim as new and original, and the other that portion of the hat where the invention lies.

It has been the custom in making firemen's

hats to use, as the tip or hold-fast for the front piece, the figure of an eagle's head, or a tiger, or fox, &c. I substitute therefor the figure of a fireman with trumpet in hand, as shown in the photographic illustration.

What I claim as my invention is—

A design for a fireman's hat, the tip or hold-fast for the front of which consists of the figure of a fireman, substantially in the manner above described.

CHS. D. P. WATTERS.
